UNITED STATES PATENT OFFICE.

JOSEPH D. AIKEN, OF TAFTVILLE, CONNECTICUT.

TROUSERS-SUPPORTER.

SPECIFICATION forming part of Letters Patent No. 707,192, dated August 19, 1902.

Application filed May 13, 1901. Serial No. 59,908. (No model.)

To all whom it may concern:

Be it known that I, JOSEPH D. AIKEN, a citizen of the United States, residing at Taftville, in the county of New London and State 5 of Connecticut, have invented certain new and useful Improvements in Trousers-Supporters, of which the following is a full, clear, and exact description.

This invention has for its object the production of an extremely simple and inexpensive device for suspending and supporting trousers, the said device being of such form that several pairs of trousers may be supported in a very limited space and so that 15 either of said pairs may be removed from or inserted in the said device without in any way interfering with or disturbing the other trousers.

The drawings annexed hereto illustrate my 20 newly-invented trousers supporter or rack, Figure 1 being a front elevation of my newly-invented device and showing in dotted lines the manner in which trousers are supported thereby. Fig. 2 is a plan view of the said 25 device. Fig. 3 shows detached a certain fixture forming an element of the trousers-hanger and serves to explain the manner in which said fixture is produced. Fig. 4 illustrates in cross-section the manner in which 30 my newly-invented device serves to support a pair of trousers.

My trousers-supporter consists, essentially, of a fixed bracket having a multiple of parallel rods projecting therefrom, the said rods 35 being located a little distance apart and inclined, as and for a purpose which I shall explain more fully later on.

Referring now to the drawings, the letter *a* indicates a bracket formed with perforations 40 *b*, adapted to receive screws by means of which the said bracket may be fixedly attached to a door or wall. As here shown, the bracket *a* is formed of sheet metal having perforated wings *a'*, that are bent outward 45 from the central or base portion until they stand parallel with each other, and into the wing-perforations are then driven rods *c*.

These rods may be of any desired number; but I have here illustrated four only.

The trousers to be supported are inverted 50 and the legs flattened and placed together, thus making four thicknesses of cloth in the leg proper and eight thicknesses at the extreme ends, where the cloth is turned in and stitched or otherwise faced down. The legs 55 thus arranged are drawn into the space between two of the rods *c*, said space being barely sufficient to receive the four thicknesses of cloth, but not wide enough to permit the entrance into or passage through the 60 said space of the thicker extreme ends of the legs. In order that the weight of the trousers may be uniformly distributed throughout the width of the leg, I incline the rods upward—that is to say, I elevate the free ends of the 65 rods—a distance equal to the angle which the ends of the legs are cut relatively to the length of the leg. When the flattened and doubled trousers-legs are drawn into the space between the rods *c*, as explained, the turned-in portion rests throughout the entire width of the leg upon the rods and being twice the thickness of the legs proper prevents the trousers from slipping downward through the narrow space. It should also be noted that the tendency of the inclined rods is to cause the trousers to slip inward—that is to say, toward the 70 bracket *a*—rather than outward and away from the supporter, as would be the case if the rods were depressed at their free ends instead of elevated.

While I have here illustrated my device as of duplex form—that is to say, with rods *c* extending outward from the bracket *a* in opposite directions—it should be understood 85 that a supporter whose capacity would be only half that of the one illustrated could be readily made by extending the rods outward from the bracket in one direction only.

The U-shaped bracket is provided at its 90 base with integral perforated ears *b'*, which afford means for securing it to the wall or other suitable support.

Having described my invention, I claim—

In a device of the character described, a bracket formed from a sheet-metal blank, said blank comprising horizontal oppositely-arranged wings having alining perforations, and vertical oppositely-arranged ears, said wings being bent to form parallel supporting-arms and the ears to provide means to secure the bracket to a support, and spring-metal arms projected through the perforations in the

wings and projecting on either side thereof to and having their opposite ends bent upwardly to form trousers-supporting members.

Signed at Norwich, Connecticut, this 4th day of May, 1901.

JOSEPH D. AIKEN.
